Des. 184,012
Patented Dec. 2, 1958

184,012

COMBINED TOOTHBRUSH AND TUMBLER HOLDER

James L. Hvale, Chicago, and William F. Meara, Oak Park, Ill., assignors to Ekco Products Company, Chicago, Ill., a corporation of Illinois

Application November 15, 1957, Serial No. 48,477

Term of patent 14 years

(Cl. D4—3)

Fig. 1 is a top perspective view of a combined toothbrush and tumbler holder, showing our new design.

Fig. 2 is a side elevational view thereof.

Fig. 3 is a top plan view thereof.

Fig. 4 is a front elevational view thereof.

The dominant features of the design reside in the portions shown in full lines.

We claim:

The ornamental design for a combined toothbrush and tumbler holder, as shown and described.
